UNITED STATES PATENT OFFICE.

JOHN M. WHEELER, OF TOLEDO, OHIO.

MATCH-SAFE.

SPECIFICATION forming part of Letters Patent No. 293,694, dated February 19, 1884.

Application filed April 9, 1883. (No model.)

To all whom it may concern:

Be it known that I, JOHN M. WHEELER, of Toledo, in the county of Lucas and State of Ohio, have invented certain Improvements in Match-Safes, of which the following is a specification.

This invention has for its object to provide a match safe or receptacle adapted to be readily secured to a wall or other surface, to be cheaply manufactured, and to be compactly stored or nested for storage or shipment.

To these ends my invention consists in the improvements which I will now proceed to describe and claim.

Of the accompanying drawings, forming a part of this specification, Figure 1 represents a front view of a match-safe embodying my improvements. Fig. 2 represents a longitudinal section of the same on line *x x*, Fig. 1; and Fig. 3 represents a transverse section on line *z z*, Fig. 1.

The same letters of reference indicate the same parts in all the figures.

In carrying out my invention I take a flat sheet of stout paper or other suitable material, cut a transverse slot, *a*, therein, and emboss a portion of the sheet below said slot to form a pocket, *P*, leaving a flat margin or marginal back, *M*, entirely surrounding said pocket. The slot *a* forms the mouth or open upper end of the pocket *P*. To the back side of said margin *M*, I apply a suitable adhesive coating, *c*, adapted, when moistened, to adhere to a supporting-surface.

It will be seen that the article thus formed constitutes a flat marginal back piece and an open-backed pocket, so that before the margin *M* is secured to a support a number of the articles can be packed or nested together in compact form. When the back side of the margin *M* is secured to a wall or other support by its adhesive coating, said support forms a back for the pocket.

I do not limit myself in all cases to an open-backed pocket, for, if desired, the adhesive back piece may cover the back of the pocket, the latter being made in a separate piece from the back piece, and suitably secured thereto.

The margin *M* may extend only to the upper end of the pocket instead of above the same, in which case it will not be necessary to slot the piece of material, the pocket extending to the upper edge of said piece. A portion, *N*, of the margin *M* is preferably coated with abrasive material adapted to ignite matches.

The open back pocket and its margin may be made of cast-iron or other metal, if desired.

I claim—

1. A match safe or receptacle composed of an open-backed pocket and a marginal back piece, said pocket and back piece being adapted to be nested in packing, the surface to which said back piece is applied forming a back for said pocket, as set forth.

2. The combination, in a match-safe, of a flat back piece, a pocket or receptacle on one side of said back piece, and an adhesive coating on the opposite side, whereby said back piece and pocket may be attached to a wall or other support, as set forth.

3. An open-backed match-safe, composed of a flat piece of material slotted transversely to form the mouth of a pocket, embossed below said slot to form the body of the pocket, and provided with a flat marginal portion entirely surrounding the pocket and having an adhesive coating on its rear surface, as set forth.

In testimony whereof I have signed my name to this specification, in the presence of two subscribing witnesses, this 5th day of April, 1883.

JOHN M. WHEELER.
